SANITARY CONTAINER

Frederick John Sessler, Sheboygan, Wis.

Application January 17, 1934, Serial No. 707,018

5 Claims. (Cl. 220—63)

My invention relates generally to sanitary containers and receptacles, and particularly to a container arranged for detachable mounting on a hospital bed or stand, for the reception of soiled articles, and an important object of my invention is to provide a simple and inexpensive container of this type which will compel disposal of soiled articles in a sanitary manner, whereby said articles will be contained in a sanitary and isolated condition after disposal, so as to avoid exposure after disposal of said articles.

Other objects and advantages of the invention will be apparent from a reading of the following description in connection with the drawings, wherein for purposes of illustration I have shown a preferred embodiment of my invention.

In the drawings:—

Figure 1 is a front elevational view of the device.

Figure 2 is a top plan view of Figure 1.

Figure 3 is an elevational view of the back of the device.

Figure 4 is a transverse vertical sectional view through Figure 3.

Figure 5 is an elevational view of the supporting tab on the back of the device.

Figure 6 is an elevational view of the mounting.

Figure 7 is a vertical transverse sectional view through Figure 4 showing the bottom construction.

Figure 8 is a top plan view of the removable bag or sack and its retainer.

Figure 9 is a perspective view of the bag or sack retainer.

Referring in detail to the drawings the numeral 5 generally designates a vertically elongated casing of generally rectangular cross section, although it may be of some other cross section if desired, which has an outwardly declining top 6 provided with a disposal opening 7. Within the true bottom of the casing 5 is an inverted U-shaped member 8 which rests on the bottom 9 to provide the elevated floor or false-bottom 10, on which the conformably shaped replaceable bag or sack 11 rests so as to bring its upper end 12 to a point slightly below the declining top 6 as shown in Figure 4.

The front of the casing is composed of a plate 13 which has a flange 14 on its upper end for resting upon the top side of the top 6 and side flanges 15, 16, respectively, which engage the outside of the side walls of the casing. The lower end part of the side flanges 15, 16 are pivoted as indicated at 17, 18 to the side walls of

the casing in such a way that the front plate 13 may be swung outwardly or forwardly to expose the interior of the casing for replacing or removing the sack or bag 11. It is to be observed that the top flange 14 and the side flanges 15, 16 are discontinuous with respect to each other, so that the top flange 14 will be free to spring relative to the plate 13, so that it may be given a position in which it will normally frictionally engage the top side of the top 6 while closed as shown in Figure 4, so as to maintain the front plate 13 in the closed position.

The back wall or plate 19 of the casing 5 has intermediate its upper and lower ends a punched out tab 20 which is of inverted generally triangular form having its apex portion cut off as indicated at 21. This supporting tab is arranged to removably seat within a conformably shaped bucket or socket 22 which is formed on the mounting generally designated 23. By this arrangement the mounting 23 may be left in place on the bed or stand, while the receptacle or container is readily removable from the mounting. By this arrangement supports or mountings 23 may be permanently installed on the beds or stands, if desired, or made to simply hook over a convenient part of the bed or stand.

The support generally designated 23 is a relatively wide plate bent into inverted J-shaped form as shown in Figures 4 and 3 to provide a wide bearing on the side member or rail of the bed or stand. An additional plate 24 is secured to the inner side of the J-shaped form to provide the socket 22, or the member 24 and the J-shaped form may be made in one piece if this be found more convenient.

For holding the bag or sack 11 up in position and to keep the mouth thereof in properly receptive relation I provide the spring generally designated 25 which is U-shaped in form and is arranged to engage three sides of the bag on the inside of the top as shown in Figures 4 and 8, and by its outwardly springing character hold the top of the bag properly in place. It is obvious that this will support the outer front side of the top of the bag independently of the front wall 13 of the casing, which is a valuable arrangement considering that the front wall 13 is to be swung outwardly and out of supporting relation to the front side of the bag when either replacing or removing the bag. It will be noted that the bight portion of the spring retainer 25 is located usually across the back of the casing as shown in Figures 4 and 8.

In order to provide convenient access to the

interior of the container or receptacle 5, and to insure against the contents of the container being exposed through the opening 7 in the top of the container, I provide a normally closed door 26 which is downwardly swingable by pressure of the hand thereon to permit the insertion into the container of the material which is to be disposed of.

The door 26 is simply a plate hinged as indicated at 27 to the upper edge of the opening 7 so that the lower end of the door will swing against the underside of the top 6 as shown in Figure 4. A suitable spring 28 has one end secured as indicated at 29 to the underside of the top 6 above the opening 7 and has its opposite end working against the lower side of the door 26. It is obvious that by this arrangement the door 26 will swing closed whenever pressure is removed therefrom. This and the other described features have the obvious result of providing for complete isolation of contaminated material within the container, and the more unobvious result of compelling the patient to avoid expectorating directly into the container and encouraging the patient to expectorate in a handkerchief or napkin, and to dispose of the napkin in the manner indicated.

Although I have shown and described herein a preferred embodiment of my invention, it is to be definitely understood that I do not desire to limit the application of the invention thereto, and any change or changes may be made in material and structure and arrangement of parts, within the spirit of the invention and the scope of the subjoined claims.

What is claimed is:—

1. A sanitary receptacle of the character described comprising a container having an opening in its top of less extent than the area of said top, an upwardly spring pressed door mounted on said top and normally closing said opening, said container being open at its front, a hinged plate arranged to close said front, a removable refuse receptacle supported on the bottom of said container, a spring within the upper part of said refuse receptacle and pressing two opposite sides and the back thereof against the side walls and back wall of the upper part of said container so as to hold the top of the refuse receptacle in refuse receiving relation to said opening in the top of the container, said spring failing to engage the front of said refuse receptacle.

2. A sanitary receptacle of the character described comprising a container having an opening in its top of less extent than the area of said top, an upwardly spring pressed door mounted on said top and normally closing said opening, said container being open at its front, a hinged plate arranged to close said front, a removable refuse receptacle supported on the bottom of said container, a spring within the upper part of said refuse receptacle and pressing two opposite sides and the back thereof against the side walls and back wall of the upper part of said container so as to hold the top of the refuse receptacle in refuse receiving relation to said spring in the top of the container, said spring failing to engage the front of said refuse receptacle, said spring

having no direct engagement with said container.

3. A sanitary receptacle of the character described comprising a container having an opening in its top of less extent than the area of said top, an upwardly spring pressed door mounted on said top and normally closing said opening, said container being open at its front, a hinged plate arranged to close said front, a removable refuse receptacle supported on the bottom of said container, a spring within the upper part of said refuse receptacle and pressing two opposite sides and the back thereof against the side walls and back wall of the upper part of said container so as to hold the top of the refuse receptacle in refuse receiving relation to said spring in the top of the container, said hinged plate being hingedly mounted on said container by its lower end so as to swing upwardly to a closed position and downwardly to an open position, respectively, in a vertical plane.

4. A sanitary receptacle of the character described comprising a container having an opening in its top of less extent than the area of said top, an upwardly spring pressed door mounted on said top and normally closing said opening, said container being open at its front, a hinged plate arranged to close said front, a removable refuse receptacle supported on the bottom of said container, a spring within the upper part of said refuse receptacle and pressing two opposite sides and the back thereof against the side walls and back wall of the upper part of said container so as to hold the top of the refuse receptacle in refuse receiving relation to said spring in the top of the container, said spring failing to engage the front of said refuse receptacle, said hinged plate being hingedly mounted on said container by its lower end so as to swing upwardly to a closed position and downwardly to an open position, respectively, in a vertical plane, the upper end of said hinged plate having a part arranged to frictionally engage the said top of the container to hold said hinged plate closed.

5. A sanitary receptacle of the character described comprising a container having an opening in its top of less extent than the area of said top, an upwardly spring pressed door mounted on said top and normally closing said opening, said container being open at its front, a hinged plate arranged to close said front, a removable refuse receptacle supported on the bottom of said container, a spring within the upper part of said refuse receptacle and pressing two opposite sides and the back thereof against the side walls and back wall of the upper part of said container so as to hold the top of the refuse receptacle in refuse receiving relation to said spring in the top of the container, said spring failing to engage the front of said refuse receptacle, said hinged plate being hingedly mounted on said container by its lower end so as to swing upwardly to a closed position and downwardly to an open position, respectively, in a vertical plane, the upper end of said hinged plate having a part arranged to frictionally engage the said top of the container to hold said hinged plate closed, and second parts on the vertical side edges thereof for similarly frictionally engaging the side walls of said container.

FREDERICK JOHN SESSLER.
